VENDING MACHINE

Filed Sept. 9, 1929

UNITED STATES PATENT OFFICE

FRED C. MYER, OF SACRAMENTO, CALIFORNIA

VENDING MACHINE

Application filed September 9, 1929. Serial No. 391,392.

This invention relates to vending machines, and more particularly to the coin control mechanism of a vending machine in which a manually operated lever releases the merchandise to be sold.

Among the objects of this invention is to provide means for normally locking the operating lever against movement, and further means to release the operating lever upon the insertion of a coin of the proper denomination.

Another object is to provide means whereby a plurality of coins may operate the machine.

15 A further object is the construction of a coin controlled vending machine with a minimum number of parts, the working of which will not be liable to become out of order.

Other objects and advantages will appear 20 as the description progresses.

In this specification and the accompanying drawings the invention is disclosed in its preferred form, but it is to be understood that it is not limited to this form because 25 it may be embodied in other forms. It is also to be understood that in and by the claims following the description, the invention is intended to be covered in whatsoever form it may be embodied.

30 In the one sheet of drawings:

Fig. 1 is a side elevation of the mechanism in part section taken on the line 1—1 in Fig. 2.

Fig. 2 is a section view taken on the line 2—2 in Fig. 1.

35 Fig. 3 is a similar view of a modified form of the invention in which two or more coins are used to release the lever.

Fig. 4 is a fragmentary detail view showing the mechanism for aligning the coins.

40 In detail the construction illustrated in Figs. 1 and 2 is as follows:

The operating lever 1 is pivoted on the shaft 2 which is fixed in the casing of the vending machine 3. The spring 3' holds the operating lever in raised position. The coin chute 4 guides the coin 5 into the groove 6 in the arm 7 which is loosely mounted on the shaft 2.

50 The projection 8 extends from the side of the lever 1 and has the groove 9 to receive

the top of the coin. A short link 10 is pivoted on the projection 8 at 11. A slot 12 is provided in the link 10 to receive the pin 13 which is fixed to the arm 7. The locking pawl 14 is pivoted at 15 on the brackets 16 and 17, 55 which are attached to the casing by the bolts 18.

The pawl 14 has the depending lug 19 which projects into the path of downward movement of the arm 7. The bar 20, traversing the brackets, carries the spring 21 which expands against the lug 19 to hold the notched end 22' of the pawl 14 under the lever 1. A spring member 23 is fixed to the casing at 24 and engages the V shaped notches 25 in the 60 arm 7 to hold the arm in one of two predetermined positions.

The operation of the device is as follows: The requisite coin is dropped down the chute 4 and guided into the grooves in the 70 projecting lug 8 and arm 7. The operating lever is then lowered manually which causes the projection 8 to bear on the top of the coin. This presses the arm 7 downward so as to contact the lug 19 of the pawl 14. The 75 pawl 14 is thereby tilted, throwing the notched end 22' out of the path of the lever 1. The operating lever continues to descend and releases the appropriate merchandise by the conventional means. Unless the requisite 80 coin is inserted in the machine, the notched end 22' of the pawl 14 prevents movement of the operating lever 1.

The coin is held between the arm 7 and the projection 8, until the completion of the 85 operative movement. The spring 23 then snaps into the lower notch 25. This causes the arm 7 to travel more rapidly, thereby increasing the distance between the projection 8 and the arm 7. This releases the coin which 90 rolls out into a suitable container. The lever 1 returns to initial position under the tension of the spring 3. The arm 7 is raised with it by means of the link 10. At the end of this movement, the spring member 23 snaps into 95 the upper notch 25. The pawl 14 is restored to normal position by the return of the arm 7 and locks the lever 1 against further movement.

It may be noted that the lever 1 is allowed 100

a limited downward movement by the pawl 14 to permit the throwing out of the end 22' if a coin is in position. However, this movement is too slight to operate the merchandise 5 releasing means.

The modified form shown in Figs. 3 and 4 works upon the same principles of operation as the already described mechanism, provision being made for the use of three coins to 10 control the mechanism.

The operating lever 26 is mounted on the shaft 27. The arms 28 and 29 have the coin receiving grooves 30 and 31 and are loosely mounted on the shaft 27. The lever 26 has 15 the projection 32 having the grooves 33 and 34 milled therein for receiving the tops of the coins. The two locking pawls 37 and 38 are pivoted on the pin 39, which extends between the brackets 35 and 36. The pawl 37 has the 20 depending lug 40 which projects into the path of travel of the arm 28. The bar 42 traverses the brackets 35 and 36 and carries the spring 41 which expands against the lug 40. This holds the notched upper end in position under 25 the lever 26. The pawl 38 has the depending lug 43. The bar 45 carries the spring 44 which expands against the lug 44 to hold the upper end in position under the lever 1. The links 47 and 48 are provided for the 30 same purpose as the link 10 in Fig. 1. The springs 49 and 50 work in suitable notches in the arms 28 and 29 similar to the notches 25 in Fig. 1. The coins 5', 51 and 52 are guided into the grooves 30—33 and 31—34 by suitable chutes.

The operation of this form of the invention is identical to the form shown in Figs. 1 and 2 in respect to the single coin 5'. This coin would operate the machine were not the lever 40 26 held by the remaining pawl 38 until the coins 51 and 52 were inserted. When all the coins are in place, the pawls 37 and 38 are both released upon movement of the lever 26, as in the simpler form.

45 It is obvious that different combinations of coins are possible. Coin 5' may be twenty-five cents, and the two coins, ten cents each, which would total forty-five cents. If all the coins were five cents, the total would be 50 fifteen cents. Any practical number of arms and locking lugs can be used to work different combinations.

Having thus described this invention, what I claim and desire to secure by Letters Patent is:

1. A vending machine coin control mechanism comprising an operating lever on a pivot, an arm on the same pivot, means to lock the lever from operating movement, 60 means on said arm for releasing said lock, and means for interposing a coin between said lever and said arm whereby the arm will unlock upon the movement of said lever.

65 2. A vending machine coin control mechanism comprising an operating lever, a pro-

jection on the side of said lever having a coin groove therein, a pivoted arm adjacent said lever, a coin groove in said arm in alignment with the coin groove in said lever, a slotted link connecting said lever and arm, a pivoted locking member having a portion in the path of motion of said arm whereby when a coin lies between said projection and said arm the movement of said lever will carry the arm against the said portion of locking member to move said locking member and allow the lever to move its full operating stroke, and a chute to guide a coin between said projection and arm.

3. A vending machine coin control mechanism comprising a casing, an operating lever pivoted in said casing, a plurality of pivoted arms adjacent to said lever, a plurality of pivoted locking members for said levers in said casing, coin guides for each of said arms, and means to receive coins between said lever and said arms whereby the movement of the lever will move the arms to release the locking means.

4. A vending machine coin control mechanism comprising a casing, an operating lever pivoted in the casing, a projection on the side of said lever, a pivoted arm adjacent said lever a pivoted locking lug for said lever, means to release said locking lug by the movement of said arm, means to receive a coin between said arm and said projection whereby the movement of the lever will move the arm to release said lever, a second pivoted arm having means to receive two coins one above another edgewise between the second arm and said projection, a second locking lug for said lever, and means on the second arm to release said lug whereby when both lugs are released the lever can complete its stroke.

In testimony whereof I have hereunto set my hand this 5th day of August A. D. 1929.

FRED C. MYER.
